Primary Examiner — Sandra Snapp*Assistant Examiner* — Holly E Thurman(74) Attorney, Agent, or Firm — David I. Roche(57) CLAIM

I claim the ornamental design for a storage box with cover, as shown and described.

DESCRIPTION

FIG. 1 is a top perspective view of the storage box showing my new design, with the cover in a closed condition;

FIG. 2 is another top perspective view with the cover shown between a closed and open condition thereof;

FIG. 3 is another top perspective view with the cover shown in an open condition thereof;

FIG. 4 is a rear view of FIG. 1;

FIG. 5 is a bottom view thereof;

FIG. 6 is a right side view thereof;

FIG. 7 is a front view thereof;

FIG. 8 is a left side view thereof; and,

FIG. 9 is a top view thereof.
